UNITED STATES PATENT OFFICE.

JAMES H. DYETT, OF BUFFALO, NEW YORK, ASSIGNOR TO HARD MANUFACTURING COMPANY, OF BUFFALO, NEW YORK.

BED-SPRING OR SPRING BED-BOTTOM.

1,270,799.

Specification of Letters Patent.

Patented July 2, 1918.

Application filed April 21, 1915. Serial No. 22,751.

To all whom it may concern:

Be it known that I, JAMES H. DYETT, a citizen of the United States, residing at Buffalo, in the county of Erie and State 5 of New York, have invented a new and useful Improvement in Bed-Springs or Spring Bed-Bottoms, of which the following is a specification.

This invention relates to bed springs or 10 bed bottoms of that kind which are provided along the side edges thereof with guards which project upwardly above the plane of the resilient spring fabric for preventing the stuffed mattress from spreading 15 laterally and from shifting sidewise on the bed spring so as to overhang the side edges thereof.

The object of the invention is to produce a practical and desirable bed spring or 20 spring bed bottom having mattress guards at the sides thereof which do not add materially to the cost of manufacture of the bed spring, but afford a reinforced side edge or guard formation therefor which will effectively retain the mattress in shape and in 25 position on the spring and will not be liable to mar or injure the mattress, or be objectionable in use.

In the accompanying drawings:

30 Figure 1 is a perspective view of a bed spring embodying the invention.

Fig. 2 is a fragmentary longitudinal sectional elevation, showing one end of one of the side guards.

35 Fig. 3 is a cross section in line 3—3, Fig. 2.

Fig. 4 is a fragmentary plan view of one corner of the bottom.

The bed spring, except as to the formation 40 of the mattress guards, may be of well known construction, consisting of a resilient bottom 10 of woven wire fabric or other suitable fabric and a rectangular frame composed of side bars 11 and cross bars 12 45 connecting the side bars and located in a plane above the same. The bottom fabric is suitably attached at its opposite ends to the end bars 12 of the frame, as for example, by the usual securing strips 13, and is 50 stretched between the end bars.

The side marginal portions of the bottom fabric 10 are folded over and fastened along their edges to the bottom fabric, thus forming at each side of the bottom a longi-

tudinal hem or casing 14. The edge of the 55 fabric can be conveniently fastened to form the hem or casing 14 by interlacing the edge coil 15 of the fabric with an intermediate coil thereof, as indicated in Fig. 3. The ends of the folded over hem portions 60 are secured to the ends of the frame, preferably between the end bars 12 and the strips 13 in the same manner as the remainder of the ends of the fabric.

Extending longitudinally in and incased 65 in each of the hems or casings 14 at the side edges of the bottom is a metal strip or thin bar 16 which is connected at its ends to the ends of the frame and held under tension, preferably by helical springs 17 attached 70 to anchoring devices 18 which are secured to the end bars of the spring frame. Two or more of the springs 17 are employed at each end of the guard strip 16, the springs being arranged and attached to the 75 guard strip 16 and the anchoring device 18 at different elevations, or one above the other, so that they act to retain the guard on edge, that is, with its greater cross dimension vertically, in addition to holding 80 it under tension. The anchoring devices 18 for the springs preferably consist of twisted metal plates having vertical inner ends to which the springs are attached and horizontal outer ends 19 fastened by screws 85 or other suitable fastenings 20 to the flat tops of the end bars of the spring frame. Anchoring devices of this form are cheap to make and apply to the spring and afford a desirable attaching means which are not 90 liable to be broken or to prevent the stacking of the springs one on another.

The guards constructed as described are very effective and desirable in use. The guard strips 16, being retained on edge by 95 their springs, hold the incasing marginal portions of the bottom fabric upright or perpendicular to the plane of the bottom so as to effectually retain the mattress in place on the spring, and since the marginal 100 hems or casings inclose the guard strip 16 substantially from end to end thereof, the guards have continuous or uninterrupted thick, rounded and smooth upper edges which will not mar or injure the mattress 105 or hurt the hands or other parts of the person in case of contact therewith, and a strong and durable connection is formed be-

tween the bottom fabric and the guard strips which will prevent the fabric from breaking away from the guard strips. The guards thus form desirable reinforcing edges for the bottom fabric in addition to serving as mattress guards. While the guard strips hold the guards upright and are practically inflexible vertically, their spring connections permit them to give and 5 they are adapted to flex laterally when the bottom yields under a weight thereon, and while the guards stiffen somewhat the sides of the resilient bottom, this is desirable rather than objectionable. The guards are 10 of less height than the thickness of the mattress.

I claim as my invention:

1. A bed spring comprising a frame, a resilient wire bottom fabric stretched between the ends of said frame and having 20 double portions forming hollow casings along the side edges of said bottom fabric, thin flexible strips extending lengthwise through said casings, and means which connect the ends of said strips to the ends of said frame and hold said strips in edge under tension whereby said strips hold said hollow casings substantially perpendicular to the plane of the bottom fabric to form mattress guards at the side edges of the bed 25 springs.

2. A bed spring comprising a frame, a flexible woven wire bottom fabric stretched between the ends of said frame, said bottom 30 fabric having perpendicular tubular edge members which are relatively high and narrow and which terminate short of the ends of said frame, means passing through said perpendicular tubular edge members to hold 35 said members perpendicular whereby they form mattress guards at the side edges of the bed spring, and means connecting said holding means under tension to the ends of said frame.

45 3. A bed spring comprising a frame, a flexible woven wire bottom fabric stretched between the ends of said frame, mattress guards at the side edges of said bottom fabric each of said guards including a tubular member of relatively high and narrow 50 cross section the bottom edge of which is formed by the bottom fabric, said members being shorter than the bottom fabric and each having a reinforced web at its ends connected to said bottom fabric and to the ends of said frame, and metal strips extending through said tubular members to hold them upright, and resilient connections between the ends of said metal strips and the ends of 55 said frame.

60 4. A bed spring comprising a frame, a flexible woven wire bottom fabric stretched between the ends of said frame and having the side edge portions thereof folded over 65 to form perpendicular tubular casings, the

ends of said tubular casings terminating in flattened webs which are attached to the ends of said frame, vertically stiff and laterally flexible strips of substantially the same length as the tubular casings extending 70 through said casings and a plurality of springs connecting the ends of said strips to the ends of the frame to hold said strips under tension and said tubular casings substantially upright to form mattress guards 75 for the bed spring.

5. A bed spring comprising a frame, a flexible metallic bottom fabric attached to the ends of said frame and having double edge portions forming casings extending 80 lengthwise at its side edges, and strips which are attached at their ends to said frame and held under tension and extend lengthwise in said casings for holding the casings substantially perpendicular to the 85 plane of said bottom to form mattress guards, the upper edge portions of the casings being disconnected from said frame ends and being solely supported by said strips.

6. A bed spring comprising a frame, a resilient bottom stretched between the ends of said frame and having longitudinal casings at its side edges, metal strips extending lengthwise in said casings, twisted anchoring plates having horizontal ends secured to the ends of said frame and vertical inner ends, and a plurality of springs at each end of said strips arranged one above the other and connecting the strips to the vertical inner ends of said anchoring plates for holding 90 said casings substantially upright.

7. A bed spring comprising a frame, a flexible metallic bottom fabric stretched between the ends of said frame and having 105 upturned portions forming substantially upright mattress guards along the side edges of the bottom, the ends of which decrease in height toward the ends of the bed spring and being disconnected at their upper portions from said frame ends, and means for retaining said guards upright.

8. A bed spring comprising a frame, a flexible metallic bottom stretched between the ends of said frame, substantially upright mattress guards extending upwardly from the side edges of the bottom, strips extending lengthwise of and connected to said guards for retaining them upright, and connections from said strips to the ends of the frame and attached to the ends of the frame substantially in the horizontal plane thereof for holding the strips under tension and for supporting said guards above said bottom, the upper edges of said guards being disconnected from said frame ends.

9. A bed spring comprising a frame, a flexible bottom fabric stretched between the ends of said frame and having casings extending lengthwise along its side edges, the 130

ends of said casings decreasing in height toward the ends of said bed spring and being disconnected at their upper portions from the ends of said frame, strips extending lengthwise in said casings, and means for holding said strips under tension for holding said casings substantially upright.

Witness my hand this 17 day of April, 1915.

JAMES H. DYETT.
